UNITED STATES PATENT OFFICE.

LEON W. ROSENTHAL, OF NEW YORK, N. Y.

CALCULATING-MACHINE.

1,237,821.

Specification of Letters Patent. Patented Aug. 21, 1917.

Application filed April 18, 1911, Serial No. 621,874. Renewed March 13, 1917. Serial No. 154,594.

To all whom it may concern:

Be it known that I, LEON W. ROSENTHAL, a citizen of the United States, residing in city of New York, county of New York,

5 State of New York, have invented certain new and useful Improvements in Calculating-Machines; and I do hereby declare the following to be a full, clear, and exact description of the invention, such as will enable others skilled in the art to which it ap-

10 pertains to make and use the same.

This invention relates to calculating machines and particularly to one adapted to mechanically perform multiplication, addition, 15 and subtraction of any numbers within the capacity for which the machine may be especially designed and for any sequence and value of the digits in any of the numbers.

20 One object is to provide a machine which performs multiplication without employing a step-by-step carriage to intermittently shift the result indicators with respect to the actuators in order to effect the ordinary process of indentation.

Another object is to provide a multiplying machine wherein both factors are first completely set up and then their product registered in a single operation.

30 Another object is to provide an adding machine wherein each number is set up and then added to the total in a single operation.

Another object is to provide a subtracting machine wherein the minuend and subtrahend are first set up and then their difference registered by a single operation; and wherein several numbers may be successively subtracted from one number in a 35 corresponding number of operations.

Another object is to provide a multiplying machine wherein the multiplicand and multiplier are exposed to view from the time they are set up and wherein the product is exposed to view upon completion of the operation.

Another object is to provide a multiplying machine wherein the digits of the multiplicand and the multiplier may each be set 45 up in any order to produce the respective factors.

Another object is to provide a calculating machine whose function may be changed from multiplication and addition to subtraction, and vice versa, by exposing to view

a different line of digits on the result indicators.

Another object is to provide a multiplying machine wherein the multiplicand and multiplier are retained in the machine until 60 reset, so that subsequent multiplications may be performed by changing only the necessary digits in either or both factors and then operating the machine as before.

Another object is to provide means for 65 clearing the result indicators at will whereby successive products may be registered or totalized as desired.

Other desirable objects in construction and operation will be made apparent by the 70 following description and will be specifically pointed out in the appended claims.

Multiplication may be performed in two general ways: to-wit, by adding in proper denominational relation the separate products of each multiplicand digit and each multiplier digit, or by adding in proper denominational relation the multiplicand factor a number of times equal to the units in each multiplier digit. Both methods require that the partial results be added in proper denominational relation. This may be accomplished by employing a step-by-step carriage to properly effect indentation of denomination of the partial results, or 80 by providing such a number of actuators and registering devices that each partial result is registered on a separate registering device, whereby the step-by-step carriage 85 may be dispensed with.

Both of the above methods of multiplication have been used heretofore, but, so far as I am aware, all prior machines employ a step-by-step carriage to effect indentation. This intermittent action interferes with the speed of operation and gives 90 rise to a variety of dissimilar movements, whereby exactness in construction is essential on account of the disengagement and subsequent engagement of parts as the relation of the actuators and the result indicators is shifted step by step.

Furthermore in order to avoid complicated construction, practically all present commercial multiplying machines require that one factor be set 100 up intermittently digit by digit and usually in the reverse order of reading the digits, so that the complete operation is comparatively slow and tedious besides requiring a certain amount of skill and diligence.

Considered in its broad aspect, the present invention embodies a non-indenting adding mechanism of any suitable form, that is an adding mechanism which is not shifted in 5 denomination step-by-step to effect indentation of denomination of the partial results. The present invention also embodies a plurality of non-indenting registering devices and actuating means therefor on which multiples of digits are represented, in combination 10 with means for relatively positioning the registering devices and actuating means, thereby constituting a multiplying mechanism. And furthermore, the present invention embodies means for selecting a series 15 of indicators of the adding mechanism in accordance with the denomination of each digit of the multiplier factor, and mechanism for effecting actuation of the registering devices to advance each indicator of each series in accordance with the sum of the digits of like denomination of the separate products of the digits of the multiplicand factor and the multiplier digit corresponding 20 to that series. In this way, the partial products are registered by the multiplying mechanism in proper denominational relation on the adding mechanism and added thereon to indicate the complete product of 25 the multiplicand and multiplier factors at the end of the operation without employing a step-by-step carriage to effect indentation of denomination of the partial results. The factors may have any number of digits up 30 to the number provided for, and the digits may have any value and any sequence.

The machine herein shown as an embodiment within the present invention operates according to a novel modification of the 40 ordinary process of multiplication, which, so far as I am aware, has never before been used in machines wherein the product is obtained mechanically, except in my co-pending application Serial No. 630,162, filed May 29, 1911, and which has only been used in 45 other computing apparatus of any kind in my co-pending application, Serial No. 460872 filed November 3rd, 1908. Briefly stated the method involves setting up the 50 multiplicand factor as many times as there are digits in the multiplier factor, then multiplying each of the digits forming the multiplicand factor by each of the multiplier digits, and finally adding the partial products 55 obtained thereby in proper denominational relation. This method is illustrated in Fig. 11, wherein the multiplication of any two factors such as 876 and 3769, giving a product of 3,301,644, is indicated. The 60 digits 8, 7 and 6 are each shown in four columns, since there are four digits in the multiplier, so that each column contains the multiplicand factor 876. Now upon multiplying each column by one of the multiplier digits 3, 7, 6 or 9, the products of the 65

separate multiplicand and multiplier digits are obtained. It is then only necessary to add the partial products in their proper denominational relation, as indicated, in order to obtain the product 3,301,644.

The multiplicand digits may be arranged in columns from top, to bottom to form the multiplicand factor, as shown, or in rows from side to side whereupon the multiplier digits would be placed at one side instead of at the bottom. The multiplicand digits may be placed in any order in either of these arrangements, either similarly or dissimilarly, the only essential condition being that each column or row, as the case may be, includes all of the multiplicand digits. Also the multiplier digits may be arranged in any order, the only essential condition being that each digit of the multiplicand factor be multiplied by each digit of the multiplier factor. Furthermore the digits of each column or row may be multiplied collectively, in groups, or successively, provided that all the partial products thereof are included in the result. And the columns or rows may be operated upon collectively, in groups, or successively, according to any order whatsoever. The only essential conditions of the entire combination and method of operation are that each multiplicand 95 digit be multiplied once and only once by each multiplier digit, and that all the separate products thereof be added in their proper denominational relation.

A machine may be built in accordance 100 with this invention for any number of digits in any of the numbers to be operated upon, and a machine so constructed will perform equally well the operations on any numbers having a number of digits less than its particular capacity. The machine herein shown as an example of the idea embodied in this invention has a capacity in multiplication of three digits in the multiplicand and four digits in the multiplier, whereby the limiting factors are 999 and 9,999. For addition its capacity is three digits in each number; and for subtraction its capacity is seven digits in the minuend and three digits in each subtrahend. I realize that this machine may readily be adapted to perform division also, but I prefer to show and describe it in the present application without this feature.

There are twelve actuators combined into 120 four identical actuator groups, whereby the number of actuators equals the product of the number of digits in the limiting factors of the machine. Each actuator bears teeth representing the elementary multiples 0 to 125 9 of the digits 1 to 9 in regular arrangement around the outer periphery of wheels, which are so arranged that the successive pairs bear the multiples of progressively increasing digits in consecutive order, each denomi- 130

nation of the partial products being represented on separate wheels. All the wheels of the three actuators in one transverse line are mechanically connected together to form 5 one actuator group so as to be collectively rotatable, whereby the teeth thereon may be brought to predetermined positions in accordance with one of the multiplier digits. Each of the other actuator groups, likewise 10 comprising three actuators, are similarly turned in accordance with each of the other multiplier digits in the particular problem. The registering devices are collectively moved in groups of four pairs along respective 15 actuators of the four actuator groups in accordance with each multiplicand digit. Either factor may be set up first and when both have been set up the teeth representing the products of all the separate multiplicand 20 and multiplier digits are in predetermined relation with respective registering devices. The registering devices are permanently connected to result indicators in such manner that the actuator teeth representing the 25 digits of the predetermined partial products are registered on the registering devices and added on the result indicators in their proper denominational relation when the operating handle is given one complete rotation. 30 The arrangement is such that the teeth of like denomination are successively registered and that the teeth of the two denominations in each partial product are successively registered, while the units are transferred to 35 result indicators of next higher denominations after each actuator group has been operated. The result indicators may be cleared or reset to zero, when desired, by a single operation. In this way the multi- 40 plicand and the multiplier are completely set up in the machine before the registering devices are actuated, and the multiplication is then performed mechanically by one rotation of the operating handle, whereupon 45 the product is indicated in convenient relation to the factors without the use of a step-by-step carriage to effect indentation. Successive products may be indicated or totalized, as desired, by clearing the result 50 indicators when required. The registering devices and the actuator group may be retained in the positions to which they were set in accordance with the digits of the factors of the previous operation. 55 Addition may be regarded as the sum of the products obtained by multiplying each of the numbers to be added by 1. Hence by successively setting up the numbers as multiplicands and multiplying each number by 60 1, the total will be registered at all times on the result indicators. Subtraction is performed by this machine by arranging a second line of digits in reverse order on the result indicators, so that the minuend set up 65 thereon is decreased by the subtrahend set

up as a multiplicand when the machine is operated as if to multiply by 1.

In the accompanying drawing illustrating an embodiment of my invention, Figure 1 is a plan view of the machine with the cover 70 removed; Fig. 2 is a longitudinal vertical elevation on section line 2—2 of Fig. 1; Fig. 3 is a longitudinal vertical elevation on section line 3—3 of Fig. 1; Fig. 4 is a longitudinal vertical elevation on section 75 line 4—4 of Fig. 1; Fig. 5 is an enlarged longitudinal vertical elevation on section line 5—5 of Fig. 1; Fig. 6 is a plan view of Fig. 5 with some of the parts thereof omitted; Fig. 7 is a perspective view of some of 80 the elements of the transfer mechanism; Fig. 8 is a transverse vertical elevation on section line 8—8 of Fig. 1; Fig. 9 is a longitudinal vertical elevation on section line 9—9 of Fig. 1 showing the clearing mecha- 85 nism; Fig. 10 is a plan view of parts of the carriages for setting the registering de- 90 vices; Fig. 11 is an example illustrating the principle upon which the invention is based; Fig. 12 is a development of one actuator; 95 Fig. 13 is a top view of the machine showing the method of indicating the factors and product upon completion of a problem in multiplication, together with a part of the internal mechanism shown in dotted lines. 95

The mechanism is inclosed in a box A having a cover A¹ with suitable apertures for the indicators and suitable openings for the operating devices.

The actuators and the teeth thereon may 100 have various arrangements and may be cast, milled or built up in any suitable way. The actuators may have the form of a cylinder, prism, endless belt, flat surface, or any other suitable form of support. The multiples or 105 partial products may be represented by teeth, cams, fingers, or any other suitable actuating means either fixed relatively to the support or projectable and retractable thereon, all of which means are well known in 110 the art and are herein broadly termed "teeth." The teeth may be relatively formed to represent the multiples of 0 to 9 of the digits 0 to 9, or the multiples 0 to 9 of the digits 1 to 9, or the multiples 1 to 9 of the 115 digits 0 to 9, the only essential condition being that all the elementary multiples of the digits be represented and that the partial products equal to 0 be represented by a blank space either on or off the actuator so that the 120 respective registering devices will not be actuated when 0 is to be registered. Furthermore the teeth may be arranged in regular or irregular order either axially of the support or at an angle thereto. The series 125 of teeth representing the elementary multiples of the digits may be arranged in various ways on the actuators. For instance, one actuator group may have a number of such series equal to the number of digits in one 130

of the limiting factors; or each series may be arranged on a separate actuator, whereby the number of actuators equals the product of the number of digits in the limiting factors of the machine; or the two denominations of the partial products may be arranged on separate supports, whereby the number of such supports equals twice that product; or the teeth constituting the series 10 may be distributed on different supports in any other way, whereby the number of supports may be variously modified. In every case the number of series of teeth representing the elementary multiples of the digits 15 equals the product of the number of digits in the limiting factors of the machine, and throughout this specification and the appended claims, I will designate the support, or supports, or parts of a support bearing 20 one complete series of teeth as an "actuator." Furthermore the actuators may be arranged in any suitable relation, either in the same or different planes, in parallel lines or tiers, in staggered or offset relation, or in any 25 other suitable way.

In the machine herein shown, there are twelve identical actuators B loosely mounted on four parallel shafts B¹ which are journaled in bearings B². (Figs. 1, 2, 3 and 8.) 30 Each actuator bears teeth B³ representing the elementary multiples 0 to 9 of the digits 0 to 9 in consecutive arrangement around the outer periphery of pairs of wheels, the multiples of 0 being represented by a blank 35 space between the actuators. As indicated in Fig. 12 by a development of the surface of one actuator, the upper row represents the elementary multiples of the digit 0, the next row representing the multiples of the digit 1, the next row representing the multiples of 2, and so on in consecutive order to the bottom row which represents the elementary multiples of the digit 9. The two 40 denominations of the partial products are arranged in adjacent lines, and in adjacent spaces around the periphery of the actuator in order to provide for the proper disposition of the two registering devices for each actuator, as will be noted later. The spaces 45 in which the teeth are arranged are of equal circumferential length so that the teeth representing the partial products are registered by turning the actuators through equal extents irrespective of the number of teeth 50 constituting the partial products. Furthermore the teeth are so arranged relatively to the registering devices that the lower denomination is registered first and then the higher denomination of each partial product. In this way all the elementary multiples 55 0 to 9 of the digits 0 to 9 are represented in regular arrangement around each actuator so that the teeth representing the product of any two digits is axially distant 60 from one end of the actuator by a number

of rows equal to one of the digits and then circumferentially distant from the column of the zero multiples by a number of columns equal to the other digit. Three of such actuators in one transverse line are mechanically fastened together so as to be collectively rotatable in one group. 70

The registering mechanism comprises registering devices, result indicators having transfer mechanism, and transmitting connections from registering devices to result indicators. The registering devices may have various forms but must be adapted to be actuated by the actuator teeth so that the partial products represented thereby may be 80 registered on the result indicators. Furthermore the registering devices and result indicators must be so connected that the partial products or parts thereof are added on the result indicators in their proper denominational relation. There may be a separate 85 registering device for each denomination of each partial product whereby the number of registering devices would equal twice the product of the number of digits in the limiting factors of the machine; or other suitable 90 arrangements may be used. In order to bring the actuators into predetermined relation in accordance with the digits of the factors to be multiplied together, the actuators, or the registering devices, or both, 95 may be moved. This result may be accomplished in setting up the factors, or otherwise, the only essential condition being that the teeth representing the predetermined 100 partial products in accordance with the digits of the factors to be multiplied together be positioned in proper relation to the registering devices to produce the product of the factors upon operating the machine. 105

In the machine herein shown, there is one registering device for each denomination of each of the partial products of the digits in the limiting factors of the machine, 110 whereby the total number thereof equals twice the product of the number of digits in said factors. The registering devices are preferably in the form of gears, although dogs or other well known devices may be 115 used for the purpose. There is a pair of registering devices C for each actuator adapted to be actuated by the teeth thereon, and the four pair in each longitudinal line are mounted in a carriage so as to be collectively moved axially of the respective actuators in a transverse line, whereby they may be moved into predetermined line with the actuator teeth representing the elementary multiples of any one of the digits 0 to 125 9. There is one carriage C¹ with registering devices for each digit in the limiting multiplicand, and each carriage is independent of the others, so that one, two, or three carriages may be moved to set up any multi- 130

5 plicand having one, two, or three digits and wherein each digit may have any value from 0 to 9. In this way each multiplicand digit in any particular problem is set up once for 10 each digit in the limiting multiplier, irrespective of the number of multiplier digits in the particular problem.

10 Each carriage C^1 comprises an arc shaped member C^2 for each of the four actuators in the same longitudinal line rigidly connected together so as to be collectively movable by means of a longitudinal bar C^3 (Fig. 2). The arc shaped members of adjacent actuators in the same transverse and longitudinal 15 lines are displaced around the actuators in order to simplify the transmitting connections from the registering devices to the result indicators. Attached to each longitudinal bar C^3 is a setting handle C^4 projecting through a slot C^5 in the cover of the machine, and by moving each setting handle the digit on the respective indicator C^6 is exposed to view through the corresponding aperture C^7 in accordance with the position 20 of the registering devices controlled thereby. (Fig. 13.) Each pair of registering devices adapted to be actuated by the teeth on the respective actuator are so disposed in position with respect to the two lines of teeth 25 representing each multiple of the digits that the teeth of lower denomination are first registered and then the teeth of higher denomination, whereby the two registering devices on the same shaft are actuated successively, as will be noted later, although this arrangement may be variously modified. Furthermore there is sufficient space between the adjacent groups of teeth to allow the 30 registering devices to be moved axially of 35 the actuators when the actuators are in any position of rest.

In multiplication the number of digits in the product is equal to, or is one less than, the sum of the number of digits in the two 40 factors, so that the number of result indicators should equal, as a minimum, the sum of the number of digits in the limiting factors of the machine. It is often desirable to increase this number of result indicators in 45 order that successive products may be totalized and also in order that larger numbers may be operated on in the other arithmetical processes. However, in the machine herein shown, there are seven result indicators C^8 50 equal in number to the sum of the digits in the limiting factors of the machine.

55 The result indicators C^8 may have any suitable form but those herein shown are cylindrical and have two lines of digits consecutively arranged in reverse order around the outer periphery, wherein 0 of one line is opposite 9 of the other line, so that the sum of any two opposite digits in the two lines is equal to nine, for the purpose to be noted 60 later. The line of digits C^9 visible through

the apertures C^{10} is for multiplication and addition, while the line of digits C^{11} is for subtraction. The slide C^{12} with apertures staggered in two lines, as shown in Fig. 13, is adapted to be moved to the right or left 70 by means of the handle C^{14} in the slot C^{13} . In the right hand position, as shown, the pointer points to M and A, designating multiplication and addition, and the line of digits C^9 on the result indicators are exposed 75 to view through the lower line of apertures in the slide C^{12} , while the upper line of apertures in the slide are closed by the cover A^1 of the machine. Similarly with the handle C^{14} at the left hand position the pointer 80 points to S, designating subtraction, and the line of digits C^{11} on the result indicators are visible through the upper line of apertures in the slide, while the lower line of apertures is closed by the cover A^1 of the 85 machine.

Various arrangements of the registering devices, the result indicators, and the transmitting connections extending from the registering devices to result indicators may be 90 used. In the machine herein shown, the carriages C^1 are displaced around the actuators in order that the registering devices of the same actuator group and of the same 95 denomination may be mounted on the same shaft. The construction is such that registering devices are moved along the shafts in setting up the multiplicand digits, but are adapted to turn the shafts when any one of them is actuated by the actuator 100 teeth. I show for this purpose a square shaft C^{15} rotatable in bearings C^{16} . (Figs. 1, 2, 3, 4 and 8.) Besides the registering devices, each shaft carries a pawl C^{17} adapted to engage a ratchet wheel C^{18} when the 105 actuators are turned in an anti-clockwise direction as seen in Fig. 2, but to slip over the teeth thereof when turned in the opposite direction, whereby the result indicators are turned in one direction only. The 110 ratchet wheels C^{18} are fastened on the shafts C^{19} which are connected by shafts C^{20} and gears C^{21} to the common shafts C^{21} , and thence by gears C^{22} to the shafts C^{23} carrying the result indicators. Each shaft C^{23} 115 also has securely mounted on it a button C^{24} for setting up a minuend in subtraction, a mutilated gear for resetting the result indicators to 0, and parts of the transfer mechanism for carrying units to the result indicators of next higher denominations, as will be noted later. The order of connecting 120 registering devices and result indicators is shown in Figs. 1 and 4, wherein the actuators are designated by a , b , c , etc., in accordance with Fig. 11. The two registering devices a^1 , a^2 actuated by actuator a are connected to result indicators of highest and next highest denominations; the registering device b^1 of actuator b is mounted on the 125 130

same shaft as a^2 , while b^2 is connected to indicator of third highest denomination; c^1 actuated by c is mounted on the same shaft as t^1 , while c^2 is connected to the result indicator of the fourth highest denomination; d^1 actuated by d is connected to the result indicator of second highest denomination while d^2 and e^1 actuated by d and e respectively are mounted on the same shaft and 5 are connected to the result indicator of third highest denomination; e^2 and f^1 are connected to the result indicator of the fourth highest denomination; f^2 is connected to the result indicator of the fifth highest 10 denomination; g^1 is connected to the third highest denomination; g^2 and h^1 are on the same shaft and connected to the fourth highest denomination; h^2 and i^1 are on the same shaft and connected to the fifth highest 15 denomination; i^2 is connected to the sixth and j^1 to the fourth; j^2 and k^1 are on the same shaft and connected to the fifth denomination; k^2 and m^1 are on the same shaft and connected to the sixth denomination; and 20 finally m^2 actuated by the actuator m is on a shaft by itself and is connected to the result indicator of the seventh highest denomination, which is the result indicator of lowest denomination. From this it is observed that two registering devices 25 are mounted on each shaft, except the ones of highest and lowest denominations, to register the teeth of respective actuators. Furthermore it will be observed that each result indicator, except those of highest and 30 lowest denominations, are actuated by a plurality of registering devices, the number depending upon the number of digits in the limiting factors of the machine. Also the result indicator of each denomination except the highest and lowest is directly actuated by two actuators, the term "directly" being used to exclude the actuation resulting from a transfer operation. 35 Although various other arrangements may be used to position the registering devices and the actuators in predetermined relation, the registering devices of each carriage in the construction herein shown are moved to the line of teeth which represent that 40 multiple of the digits 0 to 9 equal to the digit to be set up, and then each actuator group comprising the three actuators in one transverse line is turned until the teeth representing the predetermined partial products 45 are in coacting position to subsequently actuate the respective registering devices, whereby the teeth representing the separate products of each of the digits of the factors to be multiplied together are brought into 50 coacting relation with respective registering devices. The mechanism for turning the actuators in accordance with the digits of the multiplier and for indicating the digits 55 set up, are termed "multiplier numbers,"

there being one such member for each transverse group of three actuators. Each multiplier member comprises a shaft B^1 on which the three actuators are loosely mounted, a ratchet wheel D securely mounted 70 thereon, a spring pressed pawl D^1 pivoted to the actuator group and adapted to engage the respective ratchet, a handle D^2 for turning the shaft, an indicator D^3 with consecutively arranged digits securely 75 mounted thereon and adapted to expose to view the multiplier digit set up through the aperture D^4 in the cover, and a ratchet wheel D^5 fixed on the shaft and engaging with a spring pressed pawl D^6 to force the exact 80 position of the shaft and to prevent the handle from being turned backward. (Figs. 1 and 2.) Thus when a multiplier digit is to be set up, the proper handle D^2 is turned in a clockwise direction as viewed from the 85 front of the machine until the digit desired is exposed to view, thereby causing the ratchet D to turn the actuator group until the predetermined teeth thereon are brought into line with the respective registering 90 devices. The number of teeth in ratchet D is less than the number of spaces into which the periphery of the actuator is divided, for the purpose hereinafter noted. As the actuators are being turned to set up the multiplier digits, the registering devices in the path of the actuator teeth are turned in anti-clockwise direction in Fig. 2, but neither the result indicators connected thereto by the transmitting connections nor 100 the common shafts are actuated, due to the interposed pawls and ratchets C^{17} and C^{18} . Hence the registering devices may be set up either before or after the actuators are set up, and neither the registering devices 105 nor the actuators need be reset to zero after the completion of each problem. Furthermore the multiplier digits may be set up successively, in groups, or collectively, and in any order or combination whatsoever, 110 the only essential condition being that predetermined teeth on the actuators be brought into line with respective registering devices in accordance with the digits of one of the factors to be multiplied. 115 If that factor contains a number of digits less than the capacity of the machine, then the respective registering devices for the actuator groups set to zero will be in the blank spaces representing the zero 120 multiples, and hence will not be actuated upon subsequent operation of the machine. In this way the machine is adapted to perform multiplication of any two factors wherein either or both has a number of 125 digits equal to or less than the number of digits in the limiting factors of the machine. The predetermined partial products represented by actuator teeth, may be registered on the result indicators after each 130

actuator and the respective registering devices have been brought into predetermined coacting relation or after all the digits of both factors have been set up. It is desirable, although not absolutely essential, to successively register those parts of the partial products which are of the same denomination, and furthermore it is desirable to successively actuate those registering devices which are mounted on the same shaft.

In the machine herein shown, the actuators are turned to register the teeth representing the predetermined partial products, and the three actuators comprising an actuator group are turned collectively through like extents, so that the number of successive operations is four or equal to the number of digits in the limiting multiplier. The extent through which each actuator group is turned to register the teeth on the result indicators is constant, irrespective of the number of teeth registered, since the teeth are arranged in spaces of equal peripheral extent, as previously noted. Various other arrangements and methods of operation may be used. Securely attached to each actuator group is a gear E adapted to be engaged by the teeth on a respective rack E¹, and thereby turned through the angle subtended by one space on the actuator, or one-tenth of a rotation. (Figs. 1, 2 and 3.) These racks are normally held in the position shown in Fig. 3 against the action of the spring E². The machine is entirely operated by one complete rotation of the operating handle E³, whereupon the shaft E⁴, operatively connected thereto by the shaft E⁵ and the gears E⁶, is turned one complete rotation. There is a cam E⁷ and a toothed segment E⁸ fixed on the shaft E⁴ for each rack E¹, and all the cams are adapted to simultaneously allow the springs E² to pull the pivoted levers E¹⁰ out of latching engagement with the racks, whereupon the racks are simultaneously pulled by the spring E² to the position shown in dotted lines in Fig. 2. Hence the actuator groups are simultaneously turned through one-tenth of a rotation in the direction in which they were set up, so that the result indicator and the common shafts are not actuated during this period, while the shaft B¹ will also remain unturned since the pawl D¹ carried by the actuator group slips along a part of one tooth of the ratchet D to the position shown in dotted lines in Fig. 2. The toothed segments E⁸ are successively displaced angularly with a space between them of sufficient amount to operate the transfer mechanism, as will be noted later, whereby the four racks E¹ will be successively returned to their normal positions. In this way the actuator groups are successively turned backward and thereby register the teeth representing the predetermined partial

products on the result indicators in their proper denominational relation. When the operating handle has been turned through one complete rotation to the line marked "Stop" in Fig. 13, all the racks E¹ will be returned to their latched position and the actuator groups returned to their normal position, so that the machine is ready for a subsequent operation. The ratchet wheels D are provided with an indentation as shown in Fig. 2 in order that the actuator groups will not continue to rotate after the multiplier handles D² have been stopped. The function of the transfer mechanism herein shown is four fold; primarily to carry a unit to the next higher denomination when result indicators are not being actuated by the actuator teeth; secondly, to assume the position for carrying units as a result indicator passes from 9 to 0 or 0 to 9 according to the arithmetical process being performed; thirdly to provide for successive transfers when the result indicator to which a unit is to be carried is at nine in multiplication or addition and at zero in subtraction, whereby all the transfers may be made at the same time; and fourthly to reset all the transfer mechanism after the operation of carrying is completed. Securely mounted on each shaft C²³ is a result indicator C⁸, a gear F, a cam F¹ with a nose projection F² and a cam F³ with a cut-out F⁴. (Figs. 1, 5, 6 and 7.) The transfer bar F⁵ has teeth F⁶ adapted to engage the toothed wheel F⁷ which is operatively connected with shaft E⁴ by the engaging gears F⁸, so that when the operating handle is turned to operate the actuator groups the toothed wheel F⁷ is turned in the direction of the arrow in Fig. 4 and one of the four teeth thereon engages with the teeth on the transfer bar F⁵ when the actuator groups are not being operated. The transfer bar is moved to the right, as shown by the arrow in Fig. 5, and is subsequently returned after the transfer operation by means of the spring F⁹. When the transfer bar is moved to the right the result indicators to which a unit is to be carried are turned through one digit, and immediately thereafter the transfer mechanism is restored to normal position and the transfer bar returned to the position shown in Fig. 5. Each result indicator except the one of highest denomination is provided with a dog F¹⁰ pivoted on the pin F¹¹ to the transfer bar F⁵. The end F¹² of the dog is adapted to be pressed back by the nose F² of cam F¹ as the respective indicator is passing from 9 to 0 in multiplication or addition and from 0 to 9 in subtraction, and to be held in this position by means of the spring clip F¹³. The other end F¹⁴ of the dog is adapted in its raised position to engage the gear F when the transfer bar F⁵ is moved to the right and thereby turn the result in-

5 dicator of the next higher denomination through one digit in the direction of the arrow in Fig. 5, whereby one unit is added on the line of digits for multiplication and addition while one unit is subtracted on the line of digits for subtraction. For each result indicator except those of highest and lowest denominations there is a member F^{15} pivoted on the pin F^{16} . The part F^{17} is in 10 line with the cut-out F^4 of cam F^3 and is adapted to be pulled therein by the spring F^{18} when the digit 9 for multiplication and addition or the digit 0 for subtraction is exposed to view. The part F^{19} of this member 15 is prevented from rising, when the dog F^{10} is not pressed back, by the hook F^{20} , but is permitted to rise when the dog F^{10} has been pressed back to transfer a unit, so that when the dog of next lower denomination has been 20 pressed back out of the path of F^{19} , the spring F^{18} is free to pull the member F^{17} into the cut-out F^4 and thereby cause the end F^{21} to press the pin F^{22} down and thereby raise the end F^{14} to the position 25 where it will transfer a unit when the transfer bar is moved to the right. Hence when any indicator shows the digit 9 in multiplication and addition or the digit 0 in subtraction, it will quickly actuate its dog to 30 the position for transferring a unit to the indicator of next higher denomination as soon as the dog of the next lower denomination is actuated, and this operation will continue throughout the series of result indicators 35 in this position, so that successive transfers will be made throughout all the result indicators, if the occasion arises, during one movement of the transfer bar to the right. At the end of the transfer movement all the dogs F^{10} and members F^{15} will 40 be returned to their normal position as shown in Fig. 5 by means of the stationary pins F^{23} , which lie in the path of the projection F^{24} of the dogs when the dogs are in 45 the position for transferring units. In this way the end F^{14} of the dogs are brought to their depressed position just after the units have been transferred and just before the transfer bar has started its return movement, so that the result indicators to which 50 units were carried are not turned back again when the transfer bar is pulled back by the spring F^9 . Any other suitable transfer mechanism may be used.

55 Whenever desired the result indicators may be cleared in the following way: Each of the shafts C^{22} carries a mutilated gear H , so that when the rack II^1 is moved to the right by the handle II^2 , all the result indicators are simultaneously reset to zero. The rack II^1 is then automatically returned to the normal position shown in Fig. 9 by the spring H^3 .

The method of operating the machine for

65 performing multiplication will now be described. The handle C^{14} is set so as to point to M as shown in Fig. 13, and the result indicators are cleared, if necessary. The multiplicand buttons C^4 are moved to set up the digits of one factor to be multiplied, herein 70 termed the "multiplicand digits," and the multiplier handles D^2 are turned to set up the digits of the other factor, herein termed the "multiplier digits." Either factor may be set up first and the digits of either factor 75 may be set up simultaneously, in groups, or collectively, and in any order whatsoever. Furthermore the digits may be set up from the zero position or from any other position which they may have previously had. 80 The operating handle E^3 is then turned one complete rotation in the direction of the arrow in Fig. 13, whereupon the teeth representing the partial products predetermined in accordance with the separate digits of the 85 two factors are added in proper denominational relation to register the product on the result indicators. Now if the product of two other factors is to be determined, the result indicators are cleared by shifting 90 the handle II^2 to the right, the necessary digits in the two factors are changed in accordance with the second problem and the machine is operated as before. If the successive products are to be totalized then the 95 result indicators are not cleared between the separate operations.

100 Addition is performed by totalizing the successive products of each number multiplied by 1. With the handle C^{14} indicating addition as shown in Fig. 13, and with the result indicators cleared, the digits of the first number are set up by the buttons C^4 , and then the proper multiplier member D^2 is set to 1 and the other multiplier handles 105 to 0. The machine is then operated as before, whereupon the number will appear on the result indicators. The next number is similarly set up and the machine again operated, whereupon the second number is added to the first. This operation is repeated 110 until all the numbers have been added, the total appearing at all times on the result indicators.

115 To perform subtraction the handle C^{14} is moved to the left in Fig. 13 to indicate subtraction, and then the minuend is set up on the result indicators by means of the button C^{24} . The subtrahend is set up by the buttons C^4 and the proper multiplier handles D^2 is turned to 1 and the others to 0. The operating handle E^3 is then turned as before, whereupon the difference will appear on the result indicators. Other subtrahends may then be subtracted from the difference by 120 repeating the same operation. It will be observed that the minuend must be set up in such manner that no result indicator is 125

turned from 0 to 9, because then the transfer mechanism would be set to erroneously carry a unit.

In the appended claims, where I use the phrase "the limiting factors of the machine," I mean the maximum multiplicand and the maximum multiplier provided for.

My co-pending application Serial No. 630,162, filed May 29, 1911, is intended to broadly cover a calculating machine having a non-indenting adding mechanism and a non-indenting actuating mechanism therefor of any suitable kind, wherein the partial results may be added on the adding mechanism in proper denominational relation to indicate the final result without employing a step-by-step carriage for the purpose. The appended claims of this application are intended to cover a calculating machine of this kind wherein the separate digits of the products of the separate multiplicand and multiplier digits are registered on the adding mechanism in proper denominational relation to indicate thereon the final result without employing a step-by-step carriage for this purpose.

Having thus described my invention, what I claim is:

1. A calculating machine comprising actuators bearing teeth representing digits, registering devices adapted to be actuated by said teeth, result indicators having transfer mechanism, transmitting connections between the registering devices and result indicators, means for bringing the actuator teeth and registering devices into predetermined relation in accordance with the separate digits of the two factors to be multiplied together, and means for adding the digits represented by the predetermined teeth in proper denominational relation.

2. A calculating machine comprising actuators bearing teeth representing multiples of digits, registering devices adapted to be actuated by said teeth, result indicators having transfer mechanism, transmitting connections between the registering devices and result indicators, means for bringing the actuators and registering devices into predetermined relation in accordance with the digits of the factors to be multiplied together, and operating mechanism for operating the actuators.

3. A calculating machine comprising actuator groups equal in number to the digits in one of the limiting factors of the machine, wherein each group comprises a plurality of actuators, registering devices adapted to be actuated by actuator groups, result indicators having transfer mechanism, transmitting connections between the registering devices and result indicators, means for predetermined the actuation of the registering devices in accordance with the digits of the

factors to be multiplied together, and operating mechanism for operating the actuator groups.

4. A calculating machine comprising actuator groups equal in number to the number of digits in one of the limiting factors of the machine, each group being composed of a number of actuators equal to the number of digits in the other limiting factor of the machine, registering devices adapted to be actuated by the actuators, result indicators having transfer mechanism, transmitting connections between the registering devices and result indicators, means for predetermined the actuation of the registering devices in accordance with the digits of the factors to be multiplied together, and operating mechanism for operating the actuators.

5. A calculating machine comprising actuators equal in number to the product of the number of digits in the limiting factors of the machine, registering devices adapted to be actuated by actuators, result indicators having transfer mechanism, transmitting connections between the registering devices and result indicators, means for predetermined the subsequent actuation of the registering devices in accordance with the digits of the factors to be multiplied together, and operating mechanism for operating the actuators.

6. A calculating machine comprising actuators bearing teeth representing multiples of digits and being equal in number to the product of the number of digits in the limiting factors of the machine, registering devices for each actuator adapted to be actuated by the teeth thereon, result indicators having transfer mechanism, transmitting connections between the registering devices and result indicators, means for bringing the actuator teeth and registering devices into predetermined relation in accordance with the digits of the factors to be multiplied together, and operating mechanism for operating the actuators.

7. A calculating machine comprising actuators bearing teeth representing multiples of digits and being equal in number to the product of the number of digits in the limiting factors of the machine, registering devices adapted to be actuated by the actuator teeth, result indicators having transfer mechanism, transmitting connections between the registering devices and result indicators, carriages for moving the registering devices into predetermined line with actuators in accordance with the digits of one factor to be multiplied, multiplier members for moving the actuators in accordance with the digits of the other factor to be multiplied, and operating mechanism for operating the actuators.

8. A calculating machine comprising actuators, registering devices for setting up each digit of one factor to be multiplied a number of times equal to the number of digits in the limiting multiplier, result indicators having transfer mechanism, transmitting connections between the registering devices and result indicators, multiplier members equal in number to the number of digits in the limiting multiplier, each multiplier member being adapted to determine in accordance with one digit of the other factor to be multiplied the movement of those actuators on which the respective digits of the first named factor to be multiplied may be set up, and operating mechanism for operating the actuators.
9. A calculating machine comprising actuators bearing teeth representing multiples of digits and being equal in number to the product of the number of digits in the limiting multiplicand and multiplier, registering devices adapted to be actuated by the actuator teeth, result indicators having transfer mechanism, transmitting connections between the registering devices and result indicators, multiplier members equal in number to the number of digits in the limiting multiplier, each multiplier member being adapted to move in accordance with one digit of the other factor to be multiplied a number of actuators equal to the number of digits in the limiting multiplicand, and operating mechanism for operating the actuators.
10. A calculating machine comprising actuators, registering devices adapted to be actuated thereby, result indicators having transfer mechanism, transmitting connections between the registering devices and result indicators, means for predetermineding the actuation of the registering devices in accordance with the digits of the factors to be multiplied together, and operating mechanism for successively operating those actuators which effect actuation of the same result indicator.
11. A calculating machine comprising actuators bearing teeth representing multiples of digits and being equal in number to the product of the number of digits in the limiting factors of the machine, registering devices adapted to be actuated by the actuator teeth, result indicators having transfer mechanism, transmitting connections between the registering device and result indicators, means for bringing the actuator teeth and registering devices into predetermined relation in accordance with the digits of the factors to be multiplied together, and operating mechanism for successively operating those actuators which effect actuation of the same result indicators.
12. A calculating machine comprising actuators, registering devices adapted to be actuated thereby, result indicators having transfer mechanism, transmitting connections permanently connecting the registering devices and result indicators, means for predetermineding the actuation of the registering devices in accordance with the digits of the factors to be multiplied together, and operating mechanism for operating the actuators.
13. A calculating machine comprising actuators, registering devices adapted to be actuated thereby, a number of result indicators equal as a minimum to the sum of the number of digits in the limiting factors of the machine and less in number than the number of registering devices, transfer mechanism for the result indicators, transmitting connections between the registering devices and result indicators, means for predetermineding the actuation of the registering devices in accordance with the digits of the factors to be multiplied together, and operating mechanism for operating the actuators.
14. A calculating machine comprising a plurality of actuators bearing teeth representing multiples of digits, registering devices adapted to be actuated by the actuator teeth and being equal in number to twice the product of the number of digits in the limiting factors of the machine, a number of result indicators equal as a minimum to the sum of the number of digits in the limiting factors of the machine, transfer mechanism for the result indicators, transmitting connections between the registering devices and result indicators, means for bringing the actuator teeth and registering devices into predetermined relation in accordance with the digits of the factors to be multiplied together, and operating mechanism for operating the actuators.
15. A calculating machine comprising actuators, registering devices adapted to be actuated thereby, a number of result indicators equal as a minimum to the sum of the number of digits in the limiting factors of the machine, transfer mechanism for the result indicators, transmitting connections between the registering devices and result indicators so arranged that each actuator directly effects the actuation of two result indicators, means for predetermineding the actuation of the registering devices in accordance with the digits of the factors to be multiplied together, and operating mechanism for operating the actuators.
16. A calculating machine comprising actuators bearing teeth representing multiples of digits and being equal in number to the product of the number of digits in the limiting factors of the machine, registering devices adapted to be actuated by the actua-

- tor teeth, a number of result indicators equal as a minimum to the sum of the number of digits in the limiting factors of the machine, transfer mechanism, for the result 65
- 5 indicators, transmitting connections between the registering devices and result indicators so arranged that each actuator effects the direct actuation of two result indicators, means for predetermining the actuation of 70
- 10 the registering devices in accordance with the digits of the factors to be multiplied together, and operating mechanism for operating the actuators. 75
17. A calculating machine comprising actuators, registering devices adapted to be actuated thereby, result indicators having transfer mechanism, transmitting connections between the registering devices and result indicators, means for predetermining 80
- 20 the actuation of the registering devices in accordance with the digits of the factors to be multiplied together, and operating mechanism for operating the actuators through like extents. 85
- 25 18. In a calculating machine for mechanically attaining an indication of the product of any two factors of one or more digits up to the number provided for, an adding mechanism having product indicators of successive denominations, a plurality of actuators bearing teeth representing digits, a plurality of registering devices adapted to be actuated 90
- 30 by the actuators, transmitting connections between the indicators and registering devices, setting means for relatively positioning the actuators and registering devices in accordance with the separate digits of the multiplicand and the multiplier, and mechanism for effecting actuation of the registering devices to advance the indicators in accordance with the digits represented by the predetermined actuator teeth and thereby indicate the product of the multiplicand and multiplier. 95
- 45 19. A calculating machine comprising actuator groups equal in number to the number of digits in one of the limiting factors of the machine wherein each group contains a number of actuators equal to the number 100
- 50 of digits in the other limiting factor of the machine, registering devices adapted to be actuated by actuators, transmitting connections permanently connecting the registering devices and result indicators, carriages 105
- 55 for moving the registering devices into predetermined line with respective actuators in accordance with the digits of one factor to be multiplied, multiplier members for moving the actuator groups in accordance with 110
- 60 the digits of the other factor to be multiplied, and operating mechanism for operating the actuator groups through like extents. 115
20. A calculating machine comprising actuators bearing teeth representing mul- 120
- tiples of digits and being equal in number to the product of the number of digits in the limiting factors of the machine, a pair of registering devices for each actuator adapted to be actuated by the teeth thereon, result indicators having transfer mechanism, transmitting connections permanently connecting the registering devices and result indicators, carriages for moving the registering devices into predetermined relation with the actuators in accordance with the digits of one factor to be multiplied, multiplier members for moving the actuators in accordance with the digits of the other factor to be multiplied, and operating mechanism for operating the actuators through like extents. 125
21. In a calculating machine, a number of actuators equal to the product of the number of digits in the limiting factors of the machine, each of said actuators bearing teeth representing multiples of digits. 80
22. In a calculating machine, a number of actuators equal to the product of the number of digits in the limiting factors of the machine, each of said actuators bearing teeth representing partial products. 90
23. In a calculating machine, a number of actuator groups equal to the number of digits in one of the limiting factors of the machine wherein each group comprises a plurality of actuators, each bearing teeth representing digits. 95
24. In a calculating machine, a number of actuator groups equal to the number of digits in one of the limiting factors of the machine wherein each group contains a plurality of actuators bearing teeth representing multiples of digits. 100
25. In a calculating machine, a plurality of actuator groups wherein each group comprises a number of actuators equal to the number of digits in one of the limiting factors of the machine, each of said actuators bearing teeth representing digits. 105
26. In a calculating machine, a number of actuator groups equal to the number of digits in one of the limiting factors of the machine wherein each group comprises a number of actuators equal to the number of digits in the other limiting factor of the machine, each of said actuators bearing teeth representing multiples of digits. 110
27. In a calculating machine, a plurality of actuators bearing teeth representing multiples of digits, a plurality of registering devices for each actuator adapted to be actuated thereby in succession, and operating mechanism for operating the actuators. 115
28. In a calculating machine, actuators bearing teeth representing multiples of digits, a pair of registering devices adapted to be actuated thereby in succession, and operating mechanism for operating the actuators. 120
29. In a calculating machine, a plurality

- of actuators, a number of registering devices adapted to be actuated thereby equal to twice the product of the number of digits in the limiting factors of the machine.
- 5 30. In a calculating machine, a number of actuators equal to the number of digits in one of the limiting factors of the machine, and a pair of registering devices for each actuator adapted to be collectively brought 10 into predetermined line therewith in accordance with a digit to be set up.
- 15 31. In a calculating machine, a plurality of actuators on which multiples of digits are represented, and a plurality of registering devices adapted to be actuated by respective actuators.
- 20 32. In a calculating machine, actuators bearing teeth representing multiples of digits and being equal in number to the product of the number of digits in the limiting factors of the machine, and a pair of 25 registering devices for each actuator adapted to be actuated by the teeth thereon.
- 30 33. In a calculating machine, a plurality of actuators, registering devices equal in number to twice the product of the number of digits in the limiting factors of the machine, and means for bringing the actuators and registering devices into predetermined line in accordance with the digits of a number to be set up.
- 35 34. In a calculating machine, actuators bearing teeth representing multiples of digits, a plurality of registering devices adapted to be actuated by the actuator teeth, and means for bringing the actuators and registering devices into predetermined line in accordance with the digits of a number to be set up.
- 40 35. In a calculating machine, actuators bearing teeth representing multiples of digits and being equal in number to the product of the number of digits in the limiting factors of the machine, a pair of 45 registering devices for each actuator adapted to be actuated by the teeth thereon, and means for bringing the actuators and registering devices into predetermined line in accordance with the digits of a number to be set up.
- 50 36. In a calculating machine, an actuator bearing teeth representing multiples of digits, a carriage, a plurality of registering devices mounted in said carriage, and means for moving said carriage into predetermined line with said actuator in accordance with a digit to be set up.
- 55 37. In a calculating machine, a number of actuators equal to the number of digits in one of the limiting factors of the machine, a carriage, a pair of registering devices in the carriage for each actuator, and means for moving the carriage into predetermined line with the actuators in accordance with a digit to be set up.
- 60 38. In a calculating machine, a plurality of actuators bearing teeth representing multiples, a number of carriages equal to the number of digits in one of the limiting factors of the machine, a plurality of registering devices in each carriage adapted to be actuated by the actuator teeth, and means for moving the carriages into predetermined line with the actuators in accordance with the digits of a number to be set up. 65
- 70 39. In a calculating machine, a plurality of actuators, a number of carriages equal to the number of digits in one of the limiting factors of the machine, a number of registering devices in each carriage equal to twice the number of digits in the other limiting factor of the machine, and means for moving said carriages into predetermined line with the actuators in accordance with the digits of a number to be set up. 75
- 80 40. In a calculating machine, actuators bearing teeth representing multiples of digits and being equal in number to the product of the number of digits in the limiting factors of the machine, a number of carriages equal to the number of digits in one of said factors, a number of registering devices in each carriage equal to twice the number of digits in the other of said factors, and means for moving said carriages into predetermined line with said actuators in accordance with the digits of a number to be set up. 85
- 90 41. In a calculating machine, a plurality of actuators bearing teeth representing multiples of digits, multiplier members for moving respective actuators in accordance with the digits of a number to be set up, and indicating devices for indicating the digits set up. 95
- 100 42. In a calculating machine, a number of actuator groups equal to the number of digits in one of the limiting factors of the machine wherein each group comprises a number of actuators equal to the number of digits in the other limiting factor of the machine, a multiplier member for moving each actuator group in accordance with a digit to be set up, and indicating devices for indicating the digits set up. 105
- 110 43. In a calculating machine, actuators bearing teeth representing multiples of digits and being equal in number to the product of the number of digits in the limiting factors of the machine, multiplier members for moving, in accordance with each digit of one number to be set up, a number of actuators equal to the number of digits in one of said factors, and indicating devices for indicating the digits set up. 115
- 120 44. In a calculating machine, actuators bearing teeth representing multiples of digits and being equal in number to the product of the number of digits in the limit- 125

- ing factors of the machine, multiplier members equal in number to the number of digits in one of said factors, each of said multiplier members being adapted to collectively move 5 a number of actuators equal to the number of digits in the other of said factors in accordance with a digit of a number to be set up, and indicating devices for indicating the digits set up.
- 10 45. In a calculating machine, a plurality of actuators bearing teeth representing multiples of digits, a plurality of registering devices adapted to be actuated by the actuator teeth, means for bringing the actuators 15 and registering devices into predetermined line in accordance with the digits of one factor to be multiplied, and other means for subsequently bringing the predetermined actuator teeth and registering devices into 20 coacting relation in accordance with the digits of the other factor to be multiplied.
46. In a calculating machine, a number of actuator groups equal to the number of digits in one of the limiting factors of the 25 machine, registering devices for each actuator group, means for bringing actuator groups and registering devices into predetermined line in accordance with the digits of one factor to be multiplied, and other 30 means for subsequently bringing actuator groups and registering devices into coacting relation in accordance with the digits of the other factor to be multiplied.
47. In a calculating machine, a plurality 35 of actuators, registering devices equal in number to twice the product of the number of digits in the limiting multiplicand and multiplier, means for bringing into predetermined line in accordance with each digit 40 of one factor to be multiplied actuators and a number of registering devices equal to twice the number of digits in said multiplier, and other means for subsequently bringing respective actuators and registering devices into coacting relation in accordance 45 with the digits of the other factor to be multiplied.
48. In a calculating machine, a number of actuators equal to the product of the number 50 of digits in the limiting multiplicand and multiplier, a number of registering devices equal to twice the said product, means for bringing into predetermined line in accordance with each digit of one factor to be multiplied a number of actuators equal to the 55 number of digits in said multiplier and two registering devices for each actuator, and other means for subsequently bringing into coacting relation for each digit of the other 60 factor to be multiplied the respective registering devices and a number of actuators equal to the number of digits in said multiplicand.
49. In a calculating machine, a plurality 65 of actuators bearing teeth representing multiples of digits, a plurality of carriages, a plurality of registering devices in each carriage, means for moving the carriages in accordance with the digit of one factor to be multiplied, whereby registering devices are 70 brought into predetermined line with respective actuators, and means for moving the actuators in accordance with the digits of the other factors to be multiplied, whereby predetermined actuator teeth and registering devices are brought into coacting relation.
50. In a calculating machine, a number of actuator groups equal to the number of digits in one of the limiting factors of the 80 machine, a plurality of carriages, each having different registering devices for the several actuator groups, means for moving each carriage in accordance with a digit of one factor to be multiplied, and other means for 85 moving each actuator group in accordance with a digit of the other factor to be multiplied.
51. In a calculating machine, a plurality of actuators, a number of carriages equal to 90 the number of digits in one of the limiting factors of the machine, a pair of registering devices in each carriage for each digit of the other limiting factor of the machine, means for moving each carriage in accordance 95 with a digit of one factor to be multiplied, and other means for moving predetermined actuators in accordance with the digits of the other factor to be multiplied.
52. In a calculating machine, a number of 100 actuators equal to the product of the number of digits in the limiting factors of the machine, a number of carriages equal to the number of digits in one of said factors, a number of registering devices in each carriage equal to twice the number of digits in the other of said factors, means for moving each carriage in accordance with a digit of one factor to be multiplied, and other means for moving in accordance with each 110 digit of the other factor to be multiplied a number of actuators equal to the number of digits in the other of said limiting factor.
53. In a calculating machine, a plurality 115 of actuators, registering devices adapted to be actuated thereby and being equal in number to twice the product of the number of digits in the limiting factors of the machine, result indicators equal in number, as a minimum, to the sum of the number of 120 digits in said factors, and transmitting connections connecting said registering devices and said result indicators.
54. In a calculating machine, a plurality 125 of actuators bearing teeth representing multiples of digits, registering devices adapted to be actuated by the actuator teeth, a number of result indicators equal, as a minimum,

- to the sum of the number of digits in the limiting factors of the machine, and transmitting connections permanently connecting the registering devices and result indicators.
5. 55. In a calculating machine, a plurality of actuators bearing teeth representing multiples of digits, registering devices adapted to be actuated by the teeth on respective actuators and being equal in number to twice the product of the number of digits in the limiting factors of the machine, a number of result indicators equal, as a minimum, to the sum of the digits in said factors, and transmitting connections permanently connecting the registering devices and result indicators.
10. 56. In a calculating machine for mechanically attaining an indication of the product of any two factors of one or more digits up to the number provided for, an adding mechanism having product indicators of successive denominations, a plurality of actuators bearing teeth representing partial products, a plurality of registering devices adapted to be actuated by the actuators, transmitting connections between the indicators and registering devices, setting means for relatively positioning the actuators and registering devices, and mechanism for effecting actuation of the registering devices to advance the indicators in accordance with the partial products represented by the predetermined actuator teeth and thereby indicate the product of the multiplicand and multiplier.
15. 57. In a calculating machine, a plurality of actuators bearing teeth representing multiples of digits, registering devices adapted to be actuated by the actuator teeth, means for bringing the actuators and registering devices into predetermined relation in accordance with the digits of the factors to be multiplied together, and operating mechanism for operating the actuators.
20. 58. In a calculating machine, a number of actuator groups equal to the number of digits in one of the limiting factors of the machine, registering devices adapted to be actuated thereby, means for bringing the actuator groups and registering devices into predetermined relation in accordance with the digits of the factors to be multiplied together, and operating mechanism for successively operating the actuator groups.
25. 59. In a calculating machine, a plurality of actuators, registering devices adapted to be actuated thereby, means for bringing the actuators and registering devices into predetermined relation in accordance with the digits of the factors to be multiplied together, and operating mechanism for operating the actuators through like extent.
30. 60. In a calculating machine, actuators bearing teeth representing multiples of digits and being equal in number to the product of the number of digits in the limiting factors of the machine, a pair of registering devices for each actuator adapted to be actuated thereby, means for bringing the actuators and registering devices into predetermined relation in accordance with the digits of the factors to be multiplied together, and operating mechanism for operating the actuators successively in groups wherein each group comprises a number of actuators equal to the number of digits in one of the limiting factors of the machine.
35. 61. In a calculating machine, a plurality of actuators, a plurality of registering devices adapted to be actuated thereby, a plurality of result indicators, transmitting connections between the registering devices and result indicators, means for bringing the registering devices and actuators into predetermined relation in accordance with the digits of the factors to be multiplied together, and operating mechanism for effecting successive actuation of those registering devices which are connected to same result indicator.
40. 62. In a calculating machine, a plurality of actuators, registering devices adapted to be actuated thereby and being equal in number to twice the product of the number of digits in the limiting factors of the machine, a number of result indicators equal, as a minimum, to the sum of the digits in said factors, transmitting connections between the registering devices and result indicators, and operating mechanism for effecting successive actuation of those registering devices which are connected to the same result indicator.
45. 63. In a calculating machine, a plurality of actuators bearing teeth representing multiples of digits wherein the multiples are arranged in spaces of equal length, registering devices adapted to be actuated by the actuator teeth, means for bringing the actuators and registering devices into predetermined relation in accordance with the digits of the factors to be multiplied together, and operating mechanism for moving each actuator through the extent of said space.
50. 64. In a calculating machine, an adding mechanism having indicators of different denominations, a plurality of registering devices including several of the same denomination, operative connections between the registering devices and the indicators, and operating mechanism designed to operate the registering devices of the same denominations successively.
55. 65. In a calculating machine, an adding mechanism having a plurality of indicators of different denominations, a plurality of registering devices including several of each of certain denominations operatively con-

- nected to the same indicator, and operating mechanism designed to operate the registering devices of the same denomination successively.
66. In a calculating machine, an adding mechanism having a plurality of indicators, a plurality of actuators, a plurality of registering devices actuated by the actuators and comprising several ones in each of certain denominations, and operating mechanism for the actuators driven from a single source and designed to operate the actuators in such manner that the registering devices having the same denomination are actuated successively.
67. In a calculating machine, an adding mechanism, having indicators of different denominations, a plurality of registering devices wherein those having the same denomination are connected to the same indicator and wherein those having different denominations are connected to different indicators, and operating mechanism effective successively on the registering devices having the same denomination and effective simultaneously on the registering devices having different denominations.
68. In a calculating machine, a plurality of actuators, registering devices adapted to be actuated thereby, result indicators operatively connected with the registering devices, operating mechanism for operating the actuators successively, transfer mechanism for the result indicators adapted to be set for carrying units upon actuation of the result indicators, and means for carrying the units to the result indicators of next higher denominations after each successive operation.
69. In a calculating machine for mechanically attaining an indication of the product of any two factors of one or more digits up to the number provided for, a non-indenting adding mechanism comprising a plurality of product indicators of successive denominations, means for selecting a series of product indicators in accordance with the denomination of each digit of the multiplier, and mechanism for advancing the product indicators of each series in accordance with the sum of the digits of like denomination forming the partial products of the separate multiplicand digits and the multiplier digit corresponding to that series; substantially as described.
70. In a calculating machine for mechanically attaining an indication of the product of any two factors of one or more digits up to the number provided for, a non-indenting adding mechanism comprising a plurality of product indicators of successive denominations, actuating means, a plurality of registering devices adapted to be actuated by the actuating means, setting means for relatively positioning the actuating means and registering devices, means for operatively connecting predetermined registering devices with a series of product indicators in accordance with the denomination of each digit of the multiplier, and mechanism for actuating the registering device to advance the product indicators of each series in accordance with the sum of the digits of like denomination forming the partial products of the separate multiplicand digits and the multiplier digit corresponding to that series; substantially as described.
71. In a calculating machine for mechanically attaining an indication of the product of any two factors of one or more digits up to the number provided for, a non-indenting adding mechanism comprising a plurality of product indicators of successive denominations, actuators bearing teeth representing multiples of digits, registering devices adapted to be actuated by said teeth, means for relatively positioning the actuators and registering devices, means for operatively connecting predetermined registering devices with a series of product indicators in accordance with the denomination of each digit of the multiplier, and mechanism for actuating the registering devices to advance the product indicators of each series in accordance with the sum of the digits of like denomination forming the partial products of the separate multiplicand digits and the multiplier digit corresponding to that series; substantially as described.
72. In a calculating machine for mechanically attaining an indication of the product of any two factors of one or more digits up to the number provided for, a non-indenting adding mechanism comprising a plurality of product indicators of successive denominations, actuators bearing teeth representing multiples of digits, registering devices adapted to be actuated by said teeth, means for relatively positioning the actuators and registering devices, means for operatively connecting predetermined registering devices with a series of product indicators in accordance with the denomination of each digit of the multiplier, and mechanism designed to subsequently actuate the registering devices to advance each series of indicators in accordance with the product of the multiplicand and the multiplier digit corresponding to that series; substantially as described.
73. In a calculating machine for mechanically attaining an indication of the product of any two factors of one or more digits up to the number provided for, a non-indenting adding mechanism comprising a plurality of product indicators of successive denominations, actuating means, a plurality of registering devices adapted to be actuated by the

- actuating means, setting means for relatively positioning the actuating means and registering devices in accordance with the separate digits of the multiplicand and multiplier, 5 means for operatively connecting predetermined registering devices with a series of product indicators in accordance with the denomination of each digit of the multiplier, and mechanism for effecting actuation of the 10 registering devices to advance each series of product indicators in accordance with the product of the multiplicand and the multiplier digit corresponding to that series; substantially as described. 15 74. In a calculating machine for mechanically attaining an indication of the product of any two factors of one or more digits up to the number provided for, a non-indenting adding mechanism comprising a plurality of 20 product indicators of successive denominations, a plurality of non-indenting registering devices, means for operatively connecting the registering devices and product indicators, means for selecting a series of 25 product indicators in accordance with the denomination of each digit of the multiplier, and mechanism for actuating the registering devices to advance the individual product indicators in accordance with the sum of 30 the digits of like denomination of the products of the separate digits comprising the multiplicand and multiplier; substantially as described. 35 75. In a calculating machine for mechanically attaining an indication of the product of any two factors of one or more digits up to the number provided for, a non-indenting adding mechanism comprising a plurality of 40 product indicators of successive denominations, a plurality of non-indenting registering devices, means for operatively connecting the registering devices and product indicators, and mechanism for actuating the individual registering devices in accordance 45 with each digit of the products of the separate digits comprising the multiplicand and multiplier; substantially as described. 50 76. In a calculating machine for mechanically attaining an indication of the product of any two factors of one or more digits up to the number provided for, a non-indenting adding mechanism comprising a plurality of 55 product indicators of successive denominations, a plurality of non-indenting registering devices, means for operatively connecting the registering devices and product indicators, means for selecting in accordance with the denomination of each digit of the multiplier a series of product indicators 60 comprising a number thereof equal to one more than the number of digits in the multiplicand, and mechanism for actuating the registering devices to advance the individual 65 product indicators of each series in accordance with a digit of the separate products of the multiplicand digits and the multiplier digit corresponding to that series; substantially as described. 70 77. In a calculating machine for mechanically attaining an indication of the product of any two factors of one or more digits up to the number provided for, a non-indenting adding mechanism comprising a plurality of product indicators of successive denominations, actuating means, a plurality of non-indenting registering devices adapted to be actuated by the actuating means, setting means for relatively positioning the actuating means and registering devices, transmitting devices extending to the product indicators and arranged in connective relation with the actuating means through the registering devices, means for selecting a series of transmitting devices in accordance with the denomination of each digit of the multiplier, and mechanism for actuating the transmitting devices of each series to advance the product indicators in accordance with the product of the multiplicand and the multiplier digit corresponding to that series; substantially as described. 80 85 90 95 100 105 110 115 120 125

means for selecting a series of registering devices comprising a number thereof equal to twice the number of digits in the multiplicand in accordance with the denomination of each digit of the multiplier, and driving mechanism for actuating each registering device of each series to advance the connected product indicator in accordance with a digit of the product of one multiplicand

digit and the multiplier digit corresponding to that series; substantially as described.

In testimony whereof I affix my signature, in presence of two witnesses.

LEON W. ROSENTHAL.
